END PLATE FOR MULTISTACK BOBBIN MAGAZINES

Richard G. Turner, Worcester, Mass., assignor to Crompton & Knowles Loom Works, Worcester, Mass., a corporation of Massachusetts

Application May 20, 1944, Serial No. 536,545

9 Claims. (Cl. 139—247)

This invention relates to improvements in multistack weft replenishing magazines and it is the general object of the invention to provide an improved end plate for the tips of bobbins so constructed as to facilitate placement of the bobbins in the magazine without risk of damaging the weft ends extending from the bobbins.

In my prior Patent No. 2,128,974 I have shown a two-stack rocking magazine having inner and outer bobbin supporting and guiding plates for supporting a pair of horizontally spaced stacks of reserve bobbins which feed down guideways by gravity toward transfer position. Looms of the type set forth in that patent are customarily supplied with pneumatic thread holders which attract the weft ends of bobbins in the magazine. When a bobbin is placed in the magazine by hand it is usual to hold it with the left hand and lead its weft end to the thread holder with the right hand. When the bobbin is placed in its guideways its thread should be free to move downwardly without interruption.

It is an important object of my present invention to provide the outside plate of the magazine with smooth continuous thread guiding surfaces so related to each other that the weft end can slide from the top down to the bottom of the plate without danger of breakage or abrasion. The weft ends lead around guide wires supported by the plate, and this feature of my invention includes provision for mounting the guide wires so that their upper ends will be out of the path of the descending threads.

Magazines of the type referred to have generally been made with an outer plate having two guideways with spaced unconnected upper ends, thus requiring care on the part of the operator when placing a bobbin tip into the upper end of one or the other of the guideways. It is a further object of my present invention to provide the end plate of the magazine with a guide rail having portions which are inclined downwardly toward the guideways so that the bobbin requires less attention from the operator and he can give more attention to placement of the weft ends in the mouth of the thread holder. The rail extends across the upper part of the end plate and provides a continuous bobbin tip engaging surface. In order that damage to the small end of the wound mass of weft on the bobbin may be avoided I provide a wall extending upwardly from the rail the purpose of which is to engage the bobbin tip to prevent the rail from engaging and damaging the yarn on the bobbin.

It is a further object of my present invention

to provide the upper surface of the wall with continuous smooth thread guiding surface having an intermediate hook which preferably faces rearwardly so that when a thread is once placed behind it there is no chance that the thread can slip forwardly away from the rear guideway.

With these and other objects in view which will appear as the description proceeds, my invention resides in the combination and arrangement of parts hereinafter described and set forth.

In the accompanying drawing, wherein two forms of the invention are shown:

Fig. 1 is a front elevation of a magazine made according to the preferred form of my present invention, the upper part of the outer plate being broken away.

Fig. 2 is a vertical section on line 2—2, Fig. 1.

Fig. 3 is a plan view of the magazine shown in Fig. 1.

Fig. 4 is a rear view of the upper end of the back guideway showing the modified form of connection between the end plate and the thread guide wire.

Fig. 5 is a view looking from the right of Fig. 4, and

Fig. 6 is a detailed plan looking in the direction of arrow 6, Fig. 2.

Referring particularly to Figs. 1 and 3, I have shown a loom breast beam 10 on which is mounted the foot 11 of a magazine designated generally at M. The foot supports a pivot stud 12 on which is rockably mounted the inner plate 13 of the magazine. This plate is provided with front and back guideways 14 and 15, respectively, for the butts 16 of the bobbins B and B' in the front and back stacks. Stop lugs 17 and 18 engage adjusting screws 19 and 20, respectively, to limit angular movement of the plate 13 when the latter is rocked by mechanism not shown herein but set forth in the aforesaid patent. Included in the magazine are front and back tie rods 20 and 21, respectively, which are secured to the plate 13 and project outwardly away from the center of the loom.

An end plate E is secured as at 25 to the tie rods 20 and 21 and rock with the inner plate 13. The outer or end plate E is provided with front and back guideways 26 and 27, respectively, for the tips 28 of the bobbins. Guideway 26 is defined by an outer or front wall 30 and an inner or rear wall 31 both projecting laterally from a web 32 of the plate E. In similar manner, the guideway 27 is defined by an outer wall 35 and an inner wall 36 also projecting laterally from the web 32. All four of the gide walls 30, 31, 35

and 36 project inwardly or toward the interior of the magazine and have substantially vertical edges as will be understood from Fig. 1. Thus the wall 30 has an edge 40 while the rear wall 35 has an edge 41.

The magazine is equipped with mechanism not shown herein for delivering bobbins from the bottoms of the guideways, this mechanism involving both butt and tip yieldable supports which may be made in any approved manner forming no part of my present invention. The bobbins move by gravity down their respective guides and have weft ends W which extend to a thread holder H which may conveniently be of the pneumatic type acting to hold the threads taut.

The matter thus far described is of common construction and may be made as set forth in the aforesaid patent and also in other of my patents, such as Nos. 2,326,905 and 2,262,308.

In carrying one feature of my invention into effect I provide guide means for the bobbin tips and the weft ends extending from them toward the thread holder H. As shown more particularly in Fig. 2, the web 32 extends upwardly from the guideways 26 and 27 and has projecting laterally therefrom a bobbin tip engaging and supporting guide rail 45. This rail is arched and has front and back guide surfaces 46 and 47, respectively, which lead downwardly to their respective guideways. The guide rail 45 in effect is an extension of the inner walls 31 and 36 of the bobbin tip guideways, and the two parts of the rail may be connected by a reinforcing section 48 of the web formed below the rail and extending between the guideways.

The web extends above the guide rail to provide a bobbin tip engaging wall 50 having front and back downwardly inclined smooth thread guiding surfaces 51 and 52, respectively. The wall extends upwardly far enough to engage the 40 tips of bobbins which are near the rail 45 and the latter is preferably though not necessarily of less width than the length of the bobbin tip 28 which is not wound with weft. The reason for this relationship is to prevent the endmost coils of weft on the bobbin near the tip from engaging the rail and being damaged thereby when the bobbin is being placed in the magazine.

The upper part of the wall 50 is formed with a rearwardly facing hook 55 which prevents a thread 50 in engagement with surface 52 from passing over the top of the wall and sliding down the surface 51. This hook 55 is of particular use when placing bobbins in the rear stack of the magazine. Wall 50 is integral with the rail 45 and the upper ends of walls 30, 31, 35 and 36, and joins these parts together to reinforce the upper end of plate E.

Another feature of my invention relates to the manner of attaching the upper ends of thread 60 guide wires 60 and 61 to the end plate E adjacent to the upper end of the guideways 26 and 27. I illustrate two types of connection between these wires and the end plate E, the preferred form being shown, for instance, in Figs. 2 and 6, and the modified form being shown in Figs. 4 and 5. In both forms of the invention the wires 60 and 61 extend downwardly along the outer walls 30 and 35 and are curved at their lower ends as at 62 and provided with thread hooks 63. The lower ends of the guide wires are held in the bottom of the plate E as at 64 in the usual manner.

As these guide wires have been used heretofore they have interfered with the free downward movement of the weft ends attached to bobbins 75

being inserted into the magazine. In both forms of the invention provision is made to attach the upper end of these guide wires to the plate E in such a manner that they will be in non-interfering position with respect to the weft ends. In the preferred form, see Figs. 2 and 6, the front and back walls 30 and 35 are provided, respectively, with outwardly extending lugs 65 and 66, the former extending forwardly and the latter extending rearwardly from the center of the end plate. Each lug is provided with a notch 67, see particularly Fig. 6, extending from the corresponding edge 40 or 41 outwardly toward the web 32, and the upper end of the guide wire has a short bend or horizontal part 68 located in the notch and extending into the lug. The lugs 65 and 66 are provided with outer thread guiding surfaces 70 and 71, respectively, which in effect are continuations of thread guide surfaces 51 and 52, respectively, of the wall 50.

When fresh bobbins are being inserted into the magazine the relation of their weft ends to the guide wire and lugs will be substantially as indicated in Fig. 3. When a bobbin B' is being placed in the rear stack of the magazine its tip will be placed on surface 47 of the rail 45 in some such position as indicated at I, Fig. 2, and its weft end W' will extend over and in contact with some part of the surface 52 and will then lead downwardly either to the thread holder or to the operator's hand, see light dotted lines, Fig. 2. As the operator moves the bobbin downwardly and rearwardly along surface 47 its tip will enter guideway 27 as at II, Fig. 2, and the thread will slide over surface 52 on to surface 71, see heavy dotted lines, Fig. 2. As the bobbin continues its downward movement its thread W' will pass through the position shown in dot and dash lines in Fig. 3, extending across the notch 67 out of engagement with the upper bent end 68 of the guide wire 61. The thread therefore is able to move downwardly without being caught by the guide wire or the lug 66 and when the bobbin is released by the operator it falls down in the stack. If during this operation the thread should by any circumstance tend to move forwardly it will be arrested by the hook 55 and remain on that part of the wall 50 corresponding to the stack or guideway which its bobbin is to occupy.

In similar manner, when a bobbin B indicated in dot and dash lines in Fig. 3 is being placed in the front stack its weft ends W' will extend across the front notch and not be engaged by the upper end of the front guide wire 60.

In the modified form of the invention shown in Figs. 4 and 5, wherein the rear guide wire only is shown, the wire 75 corresponding to wire 61 extends upwardly along the guide wall 35 much in the same manner as that illustrated in Figs. 1, 2 and 3, but instead of being bent horizontally to enter the lug it is bent as at 76 and enters the under side of the lug 77 as at 78. The lug is also perfectly formed with a rounded upper surface 79 over which the thread may slide as it moves downwardly. In the form of the invention shown in Figs. 4 and 5 it is unnecessary to cut notches in the lugs, and the upper end of the guide wire will be held in the lug due to the fact that its lower end is held as at 64 to the bottom of the end plate E.

It is believed that the operation of the invention will be apparent from the foregoing description. The bobbins have their tips supported and guided by one or another of the surfaces 46 or 47, depending upon whether the bobbins are

to occupy the front or the back stack, and the weft ends of the bobbins extend over the wall 50 in engagement with the corresponding guide surface 51 or 52. When the bobbin moves downwardly its weft end slides over smooth continuous surfaces which offer no interruption to its downward movement. In the preferred form of the invention the upper end of the guide wires are received in notches while in the modified form the upper end of the guide wires enter the under side of the lugs. The curved surface 79 can be used in both forms of the invention.

From the foregoing it will be seen that I have provided an improved bobbin tip guiding end plate for a multistack magazine wherein the tops of the guideways are connected by a bobbin rail and an upwardly extending wall for the purpose of engaging the bobbin tips and preventing them from moving out of proper relation with respect to the end plate when being inserted in the bobbin stacks. The rail extends from the inner wall 31 across to the other inner wall 36, while the wall 50 extends from the outer wall 30 across to the rear outer wall 35. The wall 50 and rail are preferably formed integral with the end plate E and join the upper ends of the front and back guideways not only for the purposes already mentioned, but also to reinforce them. It will also be seen that the wall has a rearwardly facing hook 55 which prevents movement of a thread in contact with guide surface 52 across the top of the end plate to the forward guide surface 51 when bobbins are being placed in the rear stack. Furthermore, the upper ends of the guide wires are attached to the end plate in such manner that they present no horizontal surface which can interfere with downward movement of the weft ends. Thus, in the preferred form the notches 67 receive the horizontal end 68 of the wires, while in the modified form of the invention the wires enter the under side of their respective lugs. In both forms of the invention the lugs and adjacent parts of the outer walls 30 and 35 may be formed with the curved surfaces 79.

Having thus described my invention it will be seen that changes and modifications may be made therein by those skilled in the art without departing from the spirit and scope of the invention and I do not wish to be limited to the details herein disclosed, but what I claim is:

1. In a weft replenishing magazine having front and back horizontally spaced substantially vertical stacks of reserve bobbins, an end plate for the tips of the bobbins having vertical tip guideways, a vertical wall extending across the top of the end plate and joining the guideways and having front and back thread guiding surfaces along the top thereof extending from the outside of one guideway across to the outside of the other guideway, and a thread guide associated with each guideway and extending downwardly from the corresponding thread guiding surface.

2. In a weft replenishing magazine having two horizontally spaced substantially vertical stacks of reserve bobbins, an end plate for the tips of the bobbins, front and back pairs of vertical walls on said plate, each pair having an inner and an outer wall, a rail extending continuously from one inner wall to the other inner wall and having the front and rear ends thereof inclined downwardly to the front and back inner walls, respectively, a web extending above the rail and from one outer wall to the other outer wall and

having a top thread guiding edge inclined downwardly toward each outer wall, and a thread hook on the top of said web facing rearwardly to prevent a thread on the rear part of said edge from sliding along said edge to the front part thereof.

3. In a weft replenishing magazine having two horizontally spaced substantially vertical stacks of reserve bobbins, an end plate for the tips of the bobbins, front and back pairs of vertical walls on said plate, each pair having an inner and an outer wall, and a web joining said walls and having a thread guiding edge formed in front and rear sections, the front section extending upwardly and rearwardly from the outer wall of the front pair of walls and the rear section extending upwardly and forwardly from the outer wall of the back pair of walls.

4. In a weft replenishing magazine having two horizontally spaced substantially vertical stacks of reserve bobbins, an end plate for the tips of the bobbins, front and back pairs of vertical walls on said plate, each pair having an inner and an outer wall, a web joining said walls and having a thread guiding edge formed in front and rear sections, the front section extending upwardly and rearwardly from the outer wall of the front pair of walls and the rear section extending upwardly and forwardly from the outer wall of the back pair of walls, and a rearwardly facing hook between said sections preventing a thread from sliding from the rear section of said thread guiding section forwardly to the front section thereof.

5. In a weft replenishing magazine having two horizontally spaced substantially vertical stacks of reserve bobbins, an end plate for the tips of the bobbins, front and back pairs of vertical walls on said plate, each pair having an inner and an outer wall, a web joining said walls and having a thread guiding edge formed in front and rear sections, the front section extending upwardly and rearwardly from the outer wall of the front pair of walls and the rear section extending upwardly and forwardly from the outer wall of the back pair of walls, a bobbin tip supporting rail joining the inner walls of said pairs of walls and below the level of said sections of said thread guiding edge, and a rearwardly facing hook between said sections above said rail preventing a thread from sliding from the rear section forwardly to the front section.

6. An end plate for a weft replenishing magazine, said plate having front and back spaced vertical bobbin tip guideways, a bobbin tip supporting rail extending across the upper end of the plate from the rear part of the front guideway to the front part of the back guideway, and a bobbin tip engaging wall extending upwardly from said rail and across the top of the plate from the front part of the front guideway to the rear part of the back guideway, said wall having the front end thereof inclined forwardly and downwardly toward the front guideway and having the rear end thereof inclined rearwardly and downwardly toward the back guideway.

7. In a weft replenishing magazine having a substantially vertical stack of reserve bobbins, an outer bobbin tip guiding end plate for said magazine having a vertical rear bobbin tip guiding wall, a lug on the outer part of the upper end of said wall, a thread guiding wire extending along said wall to engage the weft end of a bobbin in said magazine, said lug having a thread guiding surface, and the upper end of the wire being bent and entering said lug, said lug and bent end of the

wire being so related that a taut weft end bent around said surface on the lug can pass downwardly from engagement with said surface to engagement with said wire without engaging said bent end of the latter.

8. In a weft replenishing magazine having a substantially vertical stack of reserve bobbins, an end plate for the tips of the bobbins, a vertical web forming the outer part of the plate with respect to the center of the magazine, an outside bobbin tip guiding wall extending inwardly from the web toward the interior of the magazine and having a vertical edge spaced from said web, a lug on the outer upper end of said wall having a notch therein extending from said edge toward said web, and a thread guiding wire extending along said edge and having the upper end thereof bent horizontally and located in said notch and extending into said lug, the upper rear edge of said web and the lug having continuous smooth

5 thread guiding surfaces and a taut thread leading from a bobbin in the magazine to a point beyond said web and passing downwardly along said continuous surfaces extending across said notch without engaging said horizontally bent end of said wire.

9. In a weft replenishing magazine having a substantially vertical stack of reserve bobbins, an outer bobbin tip guiding end plate for said magazine having a vertical bobbin tip guiding wall, a lug on the outer part of the upper end of said wall having a thread guiding surface, and a thread guiding wire extending along said wall and having an upper end which enters the under side of said lug so that a taut weft end bent around said surface and drawn downwardly will pass from engagement with said surface on said lug into engagement with said wire without engaging the upper end of the latter.

RICHARD G. TURNER.
